(57) **CLAIM**

The ornamental design for an air-tight container for moistened cotton applicator swabs, as shown and described.

DESCRIPTION

FIG. 1 is a perspective view of an air-tight container for moistened cotton applicator swabs showing our design; FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

In FIG. 1, the broken lines showing of environmental structure is for purposes of illustrating the air-tight container for moistened cotton applicator swabs in a condition of use. The broken lines and the structure they depict form no part of the claimed design.
